Primary Examiner — David Muller(74) *Attorney, Agent, or Firm* — Birch, Stewart, Kolasch & Birch, LLP(57) **CLAIM**

The ornamental design for a medical connector, as shown and described.

DESCRIPTION

FIG. 1 is a perspective view of a medical connector;
 FIG. 2 is a front view thereof;
 FIG. 3 is a rear view thereof;
 FIG. 4 is a left side view thereof;
 FIG. 5 is a right side view thereof; and,
 FIG. 6 is a top view thereof, including a Y-shaped slit.
 The features shown in broken lines depict environmental structure only and form no part of the claimed design.
